UNITED STATES PATENT OFFICE.

CHARLES P. HIDDEN, OF NEW YORK, N. Y.

EXPRESSION DEVICE FOR PLAYER-PIANOS AND THE LIKE.

1,102,661.

Specification of Letters Patent.

Patented July 7, 1914.

Application filed February 8, 1910. Serial No. 542,736.

To all whom it may concern:

Be it known that I, CHARLES P. HIDDEN, a citizen of the United States, residing at New York, in the borough of Manhattan and State of New York, have invented certain new and useful Improvements in Expression Devices for Player-Pianos and the like, of which the following is a full, clear, and exact description.

10 This invention relates to expression devices for pneumatic player pianos and the like, and has for its object the accomplishment by simple mechanism of results which although most desirable have, to the best of my knowledge, been hitherto unattainable.

15 My invention comprises new and wholly novel means whereby the operator of a player piano is enabled with one hand to control the accenting of any note or group 20 of notes desired no matter where such notes occur.

25 My invention also has for its object the improvement of the general tone of a piano if applied thereto when using such an expression device, there being no impairment of subdued tones as is the case when strips of felt, for example, are interposed between the hammers and strings; or when the hammer stroke is shortened.

30 The operating mechanism for my device is substantially concealed with the exception of the operating handle therefor, and the latter is so constructed that it may be hidden from view beneath the piano front when not 35 in use.

Further objects and advantages of my invention will be hereinafter set forth, and presented in the annexed claims.

Referring to the drawings, which form a 40 part hereof, and in which like characters designate like parts throughout the several views: Figure 1 is a somewhat diagrammatic section showing one form of my device applied to a player piano. Fig. 2 is a fragmentary elevation of a group of pneumatic valve cells, showing the relative disposition of the controlling valve stems which co-operate therewith. Fig. 3 is a fragmentary elevation of a portion of the indicating 45 mechanism. Fig. 4 is a perspective view of a guiding sleeve used in connection with the handle shaft. Fig. 5 is a fragmentary partial section of the upper portion of the handle drawn to an enlarged scale, and 50 showing the valve structure therein. Fig. 6 is a rear elevation of said handle, and the

supporting lugged collar therefor. Fig. 7 is a plan of the drum rotating mechanism. Fig. 8 is a fragment of music roll showing the lines thereon to be used in connection 60 with my expression device. Fig. 9 is a perspective view of a fragment of my spiral core. Fig. 10 is a perspective view of a fragment of the spiraled valve-operating sleeve or cover. Fig. 11 is a perspective view 65 of a section taken through said cover on line 11—11 of Fig. 10. Fig. 12 is a similar section taken on line 12—12 of Fig. 10. Fig. 13 is a perspective view of one end of my spiral supporting core, showing one form 70 of slot expanding rod, usable in connection therewith. Fig. 14 is a perspective view of one end of the assembled spiraled parts, showing a driving sprocket in position on the expander rod. Fig. 15 is a perspective 75 diagrammatic view showing the arrangement of the valve controlling apparatus and operating connections for the same. Fig. 16 is a section of the expander lever showing one of the pivoted sockets thereon. Fig. 17 80 is a section taken on line 17—17' of Fig. 18, showing a modified form of my spiral slot expanding means. Fig. 18 is a view of one end of the spiraled cover used in connection with such means. Fig. 19 is an elevation of 85 one end of a spiraled cover showing the straight forte effect groove therein; and Fig. 20 is a section taken through the air conduits and a valve cell of a modified form 90 of this portion of my device.

Referring now to Fig. 1, the roll box is shown at 1 having rolls 2 therein passing over a tracker 3, which has the usual tubing 4 connected thereto, each of said tubes 4 being secured to nipples 5 in the usual manner. Each nipple 5 leads into its respective diaphragm, bleed-holed pocket 6, the diaphragm being shown at 7; said diaphragm being adapted to operate the valve 8, and thereby cause the air to be withdrawn from pneumatic 9 in a well known manner. Instead of having the common conduit which is used to withdraw air from pneumatics 9 formed as a single extended passage, I divide the casing 10 thereof into three tiers 100 by parallel webs 11 and 12, said webs preferably extending through the entire length of said casing. At intervals substantially corresponding to the spacing of the diaphragm pneumatics, I provide vertical partitions 13, thus forming opposite each pneumatic a small chamber in which the valve 110

8 is adapted to reciprocate. Above the web 11 is the conduit 14, which I preferably connect to a bellows or vacuum chamber of any description by means of a nipple or nipples 15. Correspondingly, below the web 12, extends the conduit 16, which is in like manner connected to another bellows or vacuum chamber 17 by a nipple or nipples. The bellows have not been shown, as they may be, in so far as this disclosure is concerned, of the usual construction, well known in the art. Conduit 14 is preferably connected to the bellows having the higher vacuum therein, and hence, may be termed the high vacuum conduit. Between each of the partition walls 13, and preferably approximately central thereof, extends a valve stem 18 bearing in this form of my device two valves 19 and 20, of approximately the same diameter. An opening 21 is disposed in alignment with each of said valve stems in the upper side of the casing 10, and a corresponding series of openings 22 are provided in the lower portion of said casing. Each of these openings is closed by a diaphragm, those in the upper portion being designated 23 and those in the lower portion, 24. These diaphragms are secured by collars to the valve stems, so that no possible leakage of air can occur around said stems; said diaphragms being made of rubber, prepared fabric or any suitable material. Two series of brackets are provided respectively upon the upper and lower sides of casing 10, the upper brackets being designated 25 and the lower 26. These brackets serve as guides for the valve stems, so that the latter are only free to reciprocate therethrough. A spring 27 bears upon the lower collar 28 of each of said valve stems, the other end of said spring engaging the inner side of bracket 26. Under the action of these springs the valve stems are normally maintained in their uppermost position, the valves 20 being closed, and valves 19 being correspondingly open. This results in placing the pneumatics 9 in communication with the high vacuum conduit. The diaphragms may be made of substantially equal diameters, but I prefer to make the lower series 24 a trifle larger in area than the upper series 23. The valves and diaphragms should be so proportioned to each other as to effect a substantial balance of pressures, the springs 27 being principally relied upon to normally maintain valves 20 closed. Upon each of the upper ends of the stems 18 is provided a somewhat conically shaped head or button 29, and disposed in alignment with these buttons is the valve controlling device 30.

The construction of this mechanism is simple; but, I believe, decidedly novel, to this and other arts. I form either in one piece or in several, a spiraled semi-circular

sleeve or cover as shown in Fig. 10. In my preferred form, sections taken at intervals through this structure will be substantially semi-circular in outline, but the circular portion may be greater or less than 180°. 70 A warped surface is generated by the diametral elements as they advance from end to end of the structure while simultaneously rotating about the axis thereof, and the line of intersection of this surface with the cylindrical surface of the sleeve is substantially helical. The cover may be formed, if desired, of separable pieces or elements 31—32, as shown in Fig. 10; said elements being preferably semi-circular flanges 33 80 which may be bolted or secured together in any suitable manner, as by screws 34. The cover is interiorly grooved or recessed throughout its length, as at 36, and each end thereof is provided with a flange 37. A transverse section through any one of the flanged portions will afford a circular outline. This spiraled cover may be formed of various materials, such for example, as steel, porcelain, glass, wood, brass, etc., but 90 I prefer to make it of glass and in such lengths that the members can be conveniently pressed in molds. This not only affords a very cheap construction; but the surface obtained thereby is exceedingly hard 95 and of high polish, the advantage of which will be presently evident.

A core bar or supporting tube or rod 38, preferably round in section, is provided of such diameter that it will neatly fit into the holes 39 at the extremities of the spiraled cover, and through the groove 36 therein. The spiraled cover is hence, even though made of glass, supported firmly throughout its length upon the rigid metal bar 38 by 105 means of the semi-circular flanges aforesaid. After the bar is in place in the cover, the spiraled strips or elements 40 are secured to said bar by screws 41 or the like. Elements 40 fit snugly but freely between 110 the respective flange portions of the cover, so that the core is free to move only rotatively, and that through approximately 90°. The degree of movement, however, is capable of being varied considerably. One end 115 of the core bar 38, if the latter be solid, is bored out as shown at 42 in Fig. 13, and a diagonally disposed slot 43 is cut through the shell which may be thus formed in the end of the core bar as shown in Fig. 13. 120 A plunger or expander rod 44 is neatly insertable into the recess 42 and a spring 45, which bears against the end of said plunger, normally tends to drive the latter to its outer-most position. Upon one side of 125 plunger 44 is placed a T-shaped member 46, being preferably secured to the plunger or expander rod by driving the base of the T-shaped member into a slot in said rod and securing the same in any manner desired. 130

The web of the T-shaped member is disposed with respect to the axis of the plunger upon an angle which corresponds to that at which the slot 43 crosses over the surface 5 of bar 38. When the expander rod 44 is driven down into the recess in the core bar 38, it is evident that if said rod be held against rotation, the core bar 38 will rotate clockwise, and conversely, when the plunger is 10 released and allowed to spring outwardly, the bar will rotate counter-clockwise. A spiral or helical spring 47 surrounds the outermost and exposed end of the core bar 38; and one end of said spring is secured 15 to said bar at 48, while the other end is secured to the spiral cover at 49; the spring being so arranged that one side of each of the spiraled elements 40 normally tends to approach and make contact with the corresponding side or edge of the spiral cover, as 20 shown at 50 in Fig. 14. One of the sides of the spiraled cover adjacent the flange 37 is angularly cut away as at 51, and one edge of the corresponding spiraled element 40 is 25 in like manner cut away at 52, as shown in Fig. 14. The angle with respect to the cover axis at which these parts are cut corresponds to the angular disposition of the inclined sides of the T-shaped part 48, with 30 respect to the axis of the bar 48. It therefore follows that if the expander 44 be shoved in, being held against rotation meanwhile by the sprocket wheel 93 which is keyed or set-screwed to the end thereof, the 35 contacting spiraled portions of the device will be separated from each other and a slot of greater or less width will be formed which will spiral around over the length of the assembled parts through an angle of 40 approximately 180°.

In the embodiment of my invention herein shown, the slot may be expanded to such width that the arc thereof will be substantially 90°. When rod 44 is released, parts 45 32 and 40 will again approach, and the slot 50 will be narrowed down until it is practically closed. I prefer to round the edges of parts 32 and 40 in the manner shown at 54 in Fig. 17; but the radius of curvature of 55 such rounded edges may be considerable less than that shown. A groove 55 is provided along one side of the spiraled cover, said groove preferably beginning at the point 56 shown in Fig. 19 where the helical line intersects the inner edge of flange 37. This groove extends parallel to the axis of the whole device substantially from one end thereof to the other.

The spiraled valve controlling device 60 above described is suitably supported upon the respective ends thereof by brackets 57, being held against longitudinal displacement by the extremities of the core rod 38. Mounted in the bottom portion of the roll 65 box 1, is a dummy or indicator spiraled de-

vice 58 which is considerably shorter than the operating device, preferably being slightly less than the length of the roll box. The dummy or indicating device is constructed in substantially similar fashion to the valve operating device, but the several parts thereof may be of metal, and the outside of the spiraled cover 59 is preferably whitened, while the outside of the core rod 60 thereof is blackened, as by enameling or 75 oxidizing such surface. The warped surfaces constituting the flanks of the shallow slot are also suitably blackened. The outside of the dummy spiraling element 62 is also whitened, and in front of the dummy 80 is placed an arcuate screen 63 having a slot 64 therein. It will thus be seen that as the dummy is rotated, a black spot 65 of greater or less length will be exposed through slot 64, and that this spot may, further, apparently be made to move up and down the said slot. The expander rod 66 of the dummy is extended until the end thereof is substantially in alignment with the extremity of the expander rod 44 of the valve operating 90 structure. The extremity 67 of the rod 44 and the corresponding extremity of rod 66 are each somewhat pointed as shown at 67 in Fig. 14, and these pointed portions respectively engage pivoted sockets 68, said 95 sockets being pivoted to lever 69 by suitable shoulder bolts 70 or the like, and being capable of but a limited oscillatory movement thereupon by reason of limit pins 71 disposed for engagement with the respective 100 sides of said socket members. The tapered or conical ends of the expander rods are seated in their respective socket members in cavities 72 therein. These socket members substantially obviate lateral thrust upon the 105 expander rods. Lever 69 is pivoted at 73 to bracket 74, which may be secured to the inner side of the piano casing. The projecting lug 75 is formed upon one side of said lever, and said lug is adapted for engagement with an adjustable screw 76, a spring 77 normally maintaining said lug in contact with said screw. A cord or chain 78 is secured to said lever at 79, and in the construction shown, said cord passes over a small 110 pulley 80 and from thence downwardly, and is in turn secured at its lower end to bell crank 81. Bell crank 81 is pivotally supported at 82, the pivot pin being carried by any suitable bracket mounted upon a portion 115 of the piano casing. The other arm of bell crank 81 is joined to link 83 which may be disposed substantially parallel to and beneath the underside of the front of the piano. The forward extremity of said link 120 is in turn pivoted to an arm or bell crank 84, said bell crank being also supported in any suitable manner beneath the piano front. A link 85 unites the other arm of bell crank 84 to an arm of bell crank 86, the remaining 125 130

arm of said bell crank being in turn secured to a rod 87, and being normally restrained in a forward position by a spring 88. It is evident therefore that when rod 87 is pressed inwardly, link 85 will be moved in the direction of the arrow shown adjacent thereto, and in like manner, link 83 and chain or cord 78 will move in the correspondingly indicated directions. Lever 79 will be caused 5 to swing inwardly from the side of the piano casing, and thereby cause a translation of expander rods 44 and 66, resulting in spreading the slots of the spiral operating member and of the dummy to a greater or less 10 degree, and in corresponding amounts. The expander rod 66 is suitably supported by brackets 89 and 90, the latter bracket's position alone being indicated. Adjacent the outer extremity of said rod 66 is a small 15 sprocket 91 which is connected by a suitable chain 92 to a correspondingly sized sprocket 93 on the plunger or expander rod 44. Hence the spiraling members will rotate in unison and the rotation of both is accomplished by 20 means of a sprocket 94, which is positioned adjacent sprocket 93, and which is connected to a sprocket 95 mounted upon a shaft 96, chain 97 affording connection between sprockets 94 and 95. 25

30 The apparatus for rotating shaft 96 is shown in Figs. 1 and 7. The said shaft is suitably journaled at points 98 in brackets of any description which may be supported from the lower portion of the front of the piano casing, and a drum 99 is keyed or otherwise secured to shaft 96, preferably somewhat to one side of the center of the piano. A cord 100 passes over the respective ends of drum 99 and around idlers 101 and 35 102, in such fashion that the shaft may be rotated in either direction by moving the straight portion 103 of the cord which extends between idlers 101 and 102, in one direction or the other. A pair of supporting 40 brackets 104 is preferably secured to the underside of the front of the piano casing, and a bar 105 of rectangular cross section is slidably mounted in said brackets. A bolt 106 extends laterally through the center of 45 the bar 105 and the straight portion 103 of cord 100 is secured to the end of said bolt by a set screw 107 or by any other suitable means. The head of bolt 106 is shown at 50 108, and is provided with a V-shaped slot 109 having a parallel-sided recess 110 in the bottom thereof. A spring 111 normally serves to draw bar 105 toward one end of its path of movement. Beneath the piano front 55 is a bracket 112 having a hole 113 bored therethrough, and in said hole a sleeve 114 is secured by a driving fit or in any other suitable manner, the said sleeve being provided with a slot 115 of peculiar formation, shown in Fig. 4. 60

65 It will be observed that the forward end of slot 115 is in parallelism with the end of the sleeve. The hollow shaft 116 neatly fits in sleeve 114, so as to be freely movable therein, and a pin 117 in said shaft extends outwardly therefrom into engagement with slot 115. Upon the outer end of shaft 116 is a collar 118 secured in any suitable manner thereon. Said collar is provided with ears 119 between which is pivotally mounted a lug 120. Lug 120 is an integral part of a bent handle 121, said handle comprising a rearwardly extending portion 122 and an upwardly sloping portion 123. At the upper extremity of portion 123 is a handle 124. One side of said handle is formed by a member 125, said member being pivoted at 126 to a lug 127 which extends laterally outward from portion 123. The handle is grooved through a portion of the length thereof as at 128, preferably along the side adjacent the piano and a hole 129 is provided at the bottom of portion 122, through which a tube 130 of flexible rubber or the like may be passed; said tube extending thence upward through portion 123 and through a side of the handle 124 and being finally engaged with a seat 131 positioned at the inner extremity of the sleeve-like member 132, said member being driven into handle 124 or secured therein by any other suitable means. Screwed into the outer end of sleeve 132 is a valve sleeve 133, in which moves the prong 134 of a valve 135. Valve 135 is provided with an enlarged portion 136 which seats against leather washer 137 which in turn bears against the extremity of valve sleeve 133. The stem of valve 135 is slightly flattened at one extremity thereof, as shown at 136', to permit of air passing through the chamber formed in the sleeve 132, to the rubber tube 130. A spring 137' normally tends to keep the valve closed, but it is evident that lateral pressure, as for example, that readily applicable by the thumb of the operator to pivoted member 125, will cause valve 135 to open and admit air to tube 130. 70

57

extremity of rod 87 is forked as shown at 143, and a roller 144 is suitably pivoted in such forked portion. A flattened portion of the arcuate lug 138 is adapted to bear 5 against this roller and no matter in what position, within a predetermined amount of lateral movement the handle 124 be moved into, the flat face of lug 138 will remain in contact with roller 144 without causing 10 translation of rod 87. It will be observed, however, that motion of the handle toward or from the piano, will cause rod 87 to be correspondingly moved though in lesser degree. This latter movement of handle 15 124 affords therefore the means of controlling the expanding rods of the spiraled members. Mounted upon the rear end of rod 116 is an arm 145, which extends in substantial parallelism with the lug 119 of the 20 collar at the outer extremity of said shaft. Forwardly projecting from the extremity of arm 145 is a pin 146, and said pin is adapted to enter the V-shaped slot 109 of the bolt head 108 hereinbefore referred to. 25 When fully entered into said slot, the pin 146 will neatly engage the portion 110 at the base of said slot. It will be readily seen therefore, from the foregoing construction, that if handle 124 be oscillated from 30 one side to the other when pin 146 is in engagement with slot 110, the rod 116 will be rotated, thereby moving the arm 145 and bar 105 to cause the cord 100 to rotate the drum 99, whereupon the shaft 96 will 35 be correspondingly rotated in one direction or the other, and that hence the spiraled members will be so rotated.

It is desirable when the player action is not in use that the handle 124 should be re- 40 moved from sight, which is readily accomplished by rotating the same to the left through somewhat over 90°. The pin 117 will follow slot 115, and when the shaft has been rotated into the position aforesaid, the 45 said slot will permit of the shaft being advanced inwardly through bracket 112 and sleeve 114, so that the handle may be shoved rearward entirely beneath the piano front, simultaneously lifting itself into close prox- 50 imity thereto by reason of the upward trend of slot 115. While this is being done pin 146 disengages from slot 110 and bar 105 is drawn by spring 111 to the left. When the 55 handle is again drawn forward and out from under the piano front, it will necessarily ro- 60 tate through a path corresponding to that through which it previously moved. In so doing, pin 110 will enter the V-shaped slot 109, and finally the portion 110 thereof, thereby reengaging with member 108 and 65 moving the latter over toward its median position. For convenience and compactness I have chosen to position shaft 96 so as to extend through an aperture 147 in bracket 70 112. The shaft 116 has already been de-

scribed as being hollow, and the tube 130 is suitably connected to such hollow portion. At the other extremity of the shaft a flexible tube 148 is correspondingly connected, the 70 said tube extending thence to the sostenuto pneumatic. It is evident therefore that at all times the operator is able to sustain tones by merely pressing his thumb against pivoted member 125. The provision of a sostenuto pneumatic operable by the pressure of a 75 button is admittedly old, and hence I have merely diagrammatically indicated such mechanism. What I regard in this connection as distinctively novel, is the disposition of the operating button or finger piece 80 therefor upon a movable part, the function of which is to control the expression devices provided in connection therewith; a decidedly useful combination being the result and one which adapts itself to ready ma- 85 nipulation by the operator. Suffice it to say, therefore, that the admission of air to the tube 148 effects the exhaustion of the sostenuto pneumatic in the usual manner, a slight movement and pressure of the op- 90 erator's thumb against the pivoted member or finger piece 125 effecting this desired result, no matter where the handle may happen to be disposed at the time. If now handle 124 be moved to and fro in parallelism to the front of the piano, the spiraled members will be correspondingly rotated and the substantially closed slot of the operating spiral member will successively permit, if the edges of the slot be properly 95 rounded, one valve stem after another to rise into the slight depression caused by rounding the edges under the influence of its spring 27, to be immediately thereafter depressed again when the valve stem head 100 is pressed out of the spiral slot; the spring 27 being relatively quite weak when compared to the slot closing spring, and hence being unable to wedge apart the spiraled members. By now pressing handle 124 in- 105 wardly toward the piano the spiral slot is correspondingly widened, the expander or plunger rod 44 causing members 46 to sepa- 110 rate members 40 and 32 permitting a greater number of valve stems to rise at any par- 115 ticular point. By reason of the fact that the wedge-like action of the T-shaped member 46 is equally exerted upon both the spiral cover and the spiral strips or elements, the slot opens an equal amount upon each side of 120 its median point if handle 124 be merely pressed directly inward toward the piano. The paper roll, a fragment of which is indicated in Fig. 8, should preferably, although not at all necessarily, be marked 125 with two distinct lines 149—150, between which are to be found the notes to be accented. As the roll advances over the tracker, while playing, it becomes possible by means of these lines to accent any note 130

or notes which should be accented by merely moving the handle 124 in such manner as to cause the spot 65, apparently moving in slot 64 of the screen 63, to aline with the tracker alined points upon the lines 149—150.

5 By throwing lever 124 entirely to the right for example, although it may be equally well arranged to be to the left, the spiral operating member is rotated to a position where the groove 55 thereof extends in alignment with and directly over all of the valve stems. This immediately permits all of said stems to rise, closing the lower valves and throwing all of the pneumatics into 10 communication with the high vacuum conduit. When this is done the corresponding blackened line upon the dummy will cause the slot 64 to appear black for its entire extent.

15 20 In Figs. 17 and 18, I have shown a modification of the end of the spiraled parts which possesses many advantages. The spiral cover is shown at 32 and the end thereof, as shown in Fig. 18, is provided with a diagonally sloping slot 151, said slot extending from the inner face of the cover thereinto, but not entirely therethrough save for the aperture 152 provided at the inner extremity of said slot. In place of using a T-shaped 25 member 46 in this form of construction, I prefer to employ a roller 153 which is mounted upon the shoulder bolt 154, the latter being screwed firmly into the expander rod 44'. The shell-like end of core rod 38 is 30 shown slotted, the said bolt extending upward through the said slot. The slot in this instance is preferably diagonally disposed in corresponding fashion to that shown in Fig. 13. By reason of this formation, it becomes 35 possible to do away with the spring 47, since the roller 153 by reason of its close engagement with the sides of slots 151 will necessarily pull the members together or apart in a positive manner. Spring 45 40 should preferably be used however in connection with this form of device in similar fashion to that shown in Fig. 13. The roller and shoulder bolt are emplaceable in position through aperture 152.

45 50 Fig. 20 illustrates a modification of the valve system which may be used in connection with the spiraled parts in like manner to the corresponding structure shown in Fig. 1. In this form of construction, however, instead of using a high and also a low vacuum, I connect conduits 14 and 16 to the same vacuum chamber, so that the relative rarefaction is substantially the same upon each side of the pneumatic valve cells or 55 60 chambers. The respective ports leading from conduits 14 and 16 in this instance are shown at 155 and 156. The valve stem 18 is herein provided with but a single valve 157, and a small aperture 158 is provided around 65 each of said stems in the partition 12. When

the valve stem is in its downward position the vacuum in each of the valve chambers will be substantially the same as that in conduit 16, and as the apertures 158 are quite small when the valve 8 is opened in any given chamber, the rapidity with which the air in the corresponding pneumatic 9 can be withdrawn will be relatively slow, being impeded by the small size of said apertures 158. However, when the valve stem is permitted 70 to rise under the action of spring 27, the valve 157 will open and permit the exhaustion of air from such pneumatic much more rapidly, thereby causing the hammer operated by such pneumatic to strike against its 75 string or strings with greater momentum, and it follows from this that when one or more of valve stems 18 are allowed to rise through the action of the valve controlling device, the corresponding strings when 80 struck will vibrate more intensely and thereby cause such notes to be accented.

Having now disclosed the particular construction of the above embodiments of my invention, what I desire to particularly 90 point out is the results which may be obtained by the use thereof. In the first place, by varying the degree of vacuum and hence of the rate of exhaust from the pneumatics, I am enabled to accent any desired note or 95 group of notes in a given chord, and this without altering the timbre of any of the notes struck.

It has been customary to modulate the intensity of tone in pianos by employing a 100 felt strip or curtain which is made capable of being depressed and interposed between the hammers and the strings. The use of such a curtain produces a peculiar tangy 105 quality in the notes struck and the timbre is materially altered. When this device has not been employed it has been customary particularly in the player piano art, to employ some device for lifting forward the hammer rest rail or a section thereof so that 110 the hammers traverse a considerably less arc when actuated and thereby produce softer tones. This expedient is, however, also objectionable, although probably not so much as the other, in that the tone quality 115 is impaired and the timbre materially changed. This may be clearly demonstrated by still further shortening the stroke of the hammers, when even to the most unpractised ear, the thud-like quality of the tone 120 so produced will become apparent. By permitting the hammers to traverse the entire length of their stroke and merely altering the intensity of the blow delivered to them by the pneumatic, it becomes possible to 125 maintain the timbre unimpaired while altering the weight or intensity of the tone. My device hence is capable of causing one, two, or more tones to be accented and to stand out plainly from the back ground 130

formed by the remaining notes of a chord. The notes can be accented individually picking out one note at a time no matter where it may occur, or a group of notes may be similarly accented. The operator is enabled to effect this result by manipulating a single lever or handle, preferably by the left hand, and when he desires to throw off the subduing device and allow every tone struck 10 to stand out in equal degree, it is merely necessary to rotate said handle entirely over to one side until groove 55 is in engagement with all of the heads 29, of the valve stems. The sostenuto pneumatic may be applied by 15 pressing the thumb of the same hand against the side 125 of the handle and by means of the lines 149—150 on the paper, the inexperienced performer is enabled to play a piece of music with considerable expression. 20 The operator may or may not follow the guide lines 149—150 with the respective extremities of the black spot 65, as he may see fit. If he wishes to follow said lines to thereby strictly follow the accenting scheme, 25 he does so by pressing against the operating handle until the width of the black spot corresponds with that between the lines, determined by their intersections with the line of the tracker, and then by moving the handle to right or left he alines the extremities of the spot with the respective points on the 30 guide lines.

In the arrangement of parts as herein set forth, the accented notes may comprise 35 approximately one half of the whole number for which the player is adapted. Thus if an 88 note player be used, the device may be made to accent 44 notes consecutively disposed any where along the key-board. By varying the size of the spiraled parts and the arcuate measurements thereof it is possible to compass the entire register within the accented group. As this necessitates spiraled controls several inches in 40 diameter however it is desirable to limit the compass to one half of the register, which owing to the adjustability of said compass is amply sufficient for all practical purposes. Finally the radius of curvature or rounding 45 of the edges of members 32 and 40 will determine whether one, or a plurality, or none of the valve stems shall be freed at any given instant, the expander rod being in its outermost position.

50 The tone sounding devices may be of any suitable description; and I have diagrammatically indicated a hammer and string of a piano; the hammer being designated 159 and the string 160.

55 What I claim, is:

1. In a musical instrument, a plurality of note sounding parts, force applying elements co-operating with said parts, the intensity of force which said elements are capable of exerting being variable, a series of

devices for varying the intensity of force exerted by some of said elements as compared to others, and manually controlled means for actuating said devices, said means including two controlling elements movable with respect to each other and also movable together, means for moving said elements with respect to each other, and supplemental means for moving said elements together. 70

2. In a musical instrument, a plurality of note sounding parts, force applying elements co-operating with said parts, the intensity of force which said elements are capable of exerting being variable, a series of devices for varying the intensity of force exerted by some elements as compared to others, and manually controlled means for actuating said devices, said means including a handle, two controlling elements movable with respect to each other and also movable together, means, including connections to said handle, for moving said elements with respect to each other, and supplemental means, including connections to the same handle, for moving said elements together. 75 80 85 90

3. In a musical instrument, a plurality of note-sounding parts, force applying elements co-operating with said parts, the intensity of force which said elements are capable of exerting being variable, a series 95 of devices for varying the intensity of force exerted by some of said elements as compared to others, manually controlled means for actuating said devices, said means comprising a manipulating part, mechanism controlled by said part adapted to actuate materially variable numbers of devices in said series, and auxiliary co-acting mechanism for disposing said variable numbers wherever desired in the series, said co-acting mechanism also being controlled by said manipulatable part, said part being normally substantially equally free to yield to pressure exerted against portions thereof from a plurality of directions substantially 100 105 110 115 120 125 130 at right angles to each other and to actuate the first mentioned mechanism when pressure from but one of said directions is exerted against one portion, while leaving said co-acting mechanism undisturbed, and to actuate the latter while leaving the first mechanism undisturbed when a pressure at substantially right angles to said one is exerted thereagainst, both said first mentioned mechanism and said co-acting mechanism being adapted also to be simultaneously actuated by said part.

4. In a pneumatically operated musical instrument, a series of note sounding parts, a series of pneumatics therefor, a high vacuum exhaust trunk and a low vacuum exhaust trunk, a series of valves controlling communication between said pneumatics and said trunks, and means for actuating said valves at will, said means comprising a handle and 130

mechanism, controlled by said handle, having two valve-controlling elements movable with respect to each other, and means for moving said elements together.

5. In an expression device for automatic and semi-automatic instruments having a single manual, accenting means comprising a series of movable elements, a selective appliance coöperating therewith, said appliance having means for effecting successive displacements of said elements from their normal positions and means for materially varying the number of said elements operationally displaced, and means for simultaneously indicating said number.
10. In a musical instrument, a plurality of note sounding parts, force applying elements coöperating with said parts, the intensity of force which said elements are capable of exerting being variable, a series of devices for varying the intensity of force exerted by some elements as compared to others, and manually controlled means for actuating said devices, said means comprising a handle and two controlling elements actuated by movements of said handle, said two controlling elements being movable with respect to each other and also being movable together, said two elements adapted to successively actuate said devices when moved in the manner last mentioned.

7. In pneumatically operated musical instruments, a series of note sounding parts, a series of pneumatics therefor, a series of valves for said pneumatics, and a series of valve chambers, a series of elements each of which is provided with air controlling means, a plurality of air conduits, a unitary structure for actuating a materially variable number of said elements, whereby the corresponding pneumatics may open into one or another of said conduits, and co-acting mechanism for indicating the particular elements affected.

45. 8. In pneumatically operated musical instruments, a series of note sounding parts, a series of pneumatics therefor, a series of valves for said pneumatics, and a series of valve chambers, a series of elements each of which is provided with air controlling means, a plurality of valve conduits, and a rotatable cylindriform structure for actuating any one of said elements, whereby the corresponding pneumatic may open into one or another of said conduits.

9. In pneumatically operated musical instruments, a series of note sounding parts, a series of pneumatics therefor, a series of valves for said pneumatics and a series of valve chambers, a series of elements each of which is provided with air controlling means, a plurality of air conduits adapted to be placed in communication with said valve chambers, a unitary structure adapted to actuate variable members of said elements,

said structure comprising two portions adapted for movement toward and from each other, the location of said portions with respect to each other determining the number of elements to be actuated.

10. In pneumatically operated musical instruments, a series of note sounding parts, a series of pneumatics therefor, a series of valves for said pneumatics and a series of valve chambers, a series of elements each of which is provided with air controlling means, a plurality of air conduits adapted to be placed in communication with said valve chambers, a structure having a crevice therein the width of which is variable, and means for varying the width of said crevice.

11. In pneumatically operated musical instruments, a series of note sounding parts, a series of pneumatics therefor, a series of valves for said pneumatics and a series of valve chambers, a series of elements each of which is provided with air controlling means, a plurality of air conduits adapted to be placed in communication with said valve chambers, a revolvably mounted structure having a crevice therein the width of which is variable, and means for varying the width of said crevice.

12. In musical instruments, a series of note-sounding parts corresponding to an extended portion, at least, of the gamut, actuating means for said parts, and an expression device comprising means for influencing the action of said parts, said last mentioned means coöperating with said actuating means to cause accentuation of variable sized numbers of said notes and to dispose said numbers wherever desired in said portion of the gamut, said expression devices having a manually operable controlling structure adapted for substantially instant control by one hand, said structure adapted to co-act with said last mentioned means to simultaneously determine the number of notes subject to accentuation and to locate said notes where desired in said portion of the gamut, and co-acting means for simultaneously indicating the location in the gamut of substantially all of the notes so rendered subject to accentuation.

13. In musical instruments, a series of note-sounding parts corresponding to an extended portion, at least, of the gamut, actuating means for said parts, and an expression device comprising means for influencing the action of said parts, said last mentioned means coöperating with said actuating means to cause accentuation of variable sized numbers of said notes and to dispose said numbers wherever desired in said portion of the gamut, said expression device having only a single controlling handle adapted to co-act with said last mentioned means to simultaneously determine the number of notes subject to accentuation and to

locate said number where desired in said portion of the gamut, and co-acting means for indicating the number and location of notes affected.

- 5 14. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members with respect to another, in one direction, means for moving one of said members with respect to another, in another direction, and a spring for normally holding said members in predetermined relationship. 70
- 10 15. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members with respect to another, means for moving two 75
- 15 of said members together, a single lever for actuating both of said last mentioned means, and connections between said lever and said two last mentioned means. 80
- 20 16. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members with respect to another in one direction, means for moving one of said members with respect to another in another direction, and means for effecting said movements substantially simultaneously. 85
- 25 17. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members, with respect to another, in one direction, means for moving one of said members with respect to another in another direction, means for normally holding said members in predetermined relationship. 90
- 30 18. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members, with respect to another, in one direction, means for moving one of said members with respect to another in another direction, means for normally holding said members in predetermined relationship. 95
- 35 19. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members with respect to another, in one direction, means for moving one of said members with respect to another in another direction, and means for normally holding said members in predetermined relationship. 100
- 40 20. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members, with respect to another, in one direction, means for moving one of said members with respect to another in another direction, means for normally holding said members in predetermined relationship, an operating handle, and connections between said handle 105
- 45 and one of said member moving means. 110
- 46 21. In musical instruments, a series of note sounding parts, an expression device comprising an element mounted to permit a point therein to be positioned in any part of a predetermined surface, means controlled by the relative disposition of said point in said surface for determining the relative tone values producible by said note sounding parts, indicating means, and apparatus for actuating said means in substantial coincidence with the movement of said elements. 115
- 50 22. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, one at least of which is rotatable, means for rotating said rotatable member, and means for moving another of said members, the relative positions of said members, with respect to each other, determining the number of notes in a chord which are to be accented. 120
- 55 23. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members with respect to another, in one direction, means for moving one of said members with respect to another in another direction, an operating 125
- 60 24. In musical instruments, means for sounding a chord the tone values of the respective notes of which are of varying intensity, comprising note sounding devices, operating means therefor, and mechanism for regulating the intensity of action of said note sounding devices, said mechanism including a plurality of coöperating members, means for moving one of said members with respect to another, in one direction, means for moving one of said members with respect to another in another direction, an operating 130

handle, means for normally holding said members in predetermined relationship, and connections between said handle and both of said member moving means.

- 5 23. In musical instruments, means for sounding a chord the tone values of the respective notes of which are of varying intensity, comprising note sounding devices, operating means therefor, and mechanism 10 for regulating the intensity of action of said note sounding devices, said mechanism including a plurality of coöperating members, means for moving one of said members with respect to another, in one direction, means 15 for moving one of said members with respect to another in another direction, means for normally holding said members in predetermined relationship, an operating handle, and connections between said handle and 20 both of said member moving means, said handle being mounted for movement in a plurality of planes.

24. In musical instruments, means for sounding a chord the tone values of the respective notes of which are of varying intensity, comprising note sounding devices, 25 operating means therefor, and mechanism for regulating the intensity of action of said note sounding devices, said mechanism including a plurality of coöperating members, means for moving one of said members with respect to another, in one direction, means for moving one of said members with respect to another in another direction, means for 30 normally holding said members in predetermined relationship, indicating means, and connections between said indicating means and said members.

25. In musical instruments, means for 40 sounding a chord the tone values of the respective notes of which are of varying intensity, comprising note sounding devices, operating means therefor, and mechanism for regulating the intensity of action of said note sounding devices, said mechanism comprising, a plurality of coöperating members 45 rotatably mounted on a common axis, means for displacing parts of one of said members with respect to corresponding parts of another of said members, and manually controlled means for moving said members together.

26. In pneumatically operated musical instruments, a series of note-sounding parts, 55 a series of pneumatics therefor, a valve chest, a series of valves for said pneumatics and a series of valve chambers, a series of elements each of which is provided with air controlling means, a plurality of air conduits, 60 a manually operable member and coöperating means therefor for actuating any one of a plurality of said elements whereby the corresponding pneumatic may open into one or another of said conduits, said member being mounted for movement in a plurality of 65

planes and means controlled by the movement of said member into different planes for correspondingly varying the number of elements actuated.

27. In musical instruments, means for 70 sounding a chord the tone values of the respective notes of which are of varying intensity, comprising note sounding devices, operating means therefor, and mechanism for regulating the intensity of action of said note sounding devices, said mechanism including two rotatably mounted coöperating members, and means for moving said members apart to form a slot therebetween.

28. In musical instruments, means for 80 sounding a chord the tone values of the respective notes of which are of varying intensity, comprising note sounding devices, operating means therefor, and means for regulating the intensity of action of said 85 note sounding devices, said last mentioned means involving a plurality of coöperating spiraled members, and means for displacing parts of one of said members with respect to corresponding parts of another of said 90 members.

29. In musical instruments, means for 95 sounding a chord the tone values of the respective notes of which are of varying intensity, comprising note sounding devices, operating means therefor, and means for regulating the intensity of action of said note sounding devices, said last mentioned means involving a plurality of coöperating spiraled members rotatably mounted on a 100 common axis, and means for displacing parts of one of said members with respect to corresponding parts of another of said 105 members.

30. In pneumatically operated musical instruments, note sounding devices, an expression device for controlling the accentuation of notes, said devices including a series of valve stems, valves therefor, diaphragms attached to said valve stems, said 110 diaphragms each having an area substantially equal to that of one of said valves, and means for successively moving said valve stems, each of said diaphragms adapted to sustain a pressure substantially equal 115 to that on a corresponding valve.

31. In musical instruments, note sounding devices, an expression device for controlling the accentuation of notes, said device comprising an operating structure having an 120 opening therein, and an indicating structure also having an opening therein, means for closing said opening in said operating structure, in part at least, and means for simultaneously closing the opening in said 125 indicating structure.

32. In musical instruments, means for sounding a chord the tone values of the respective notes of which are of varying intensity, comprising note-sounding devices, 130

operating means therefor, and mechanism for regulating the intensity of action of said note-sounding devices, said mechanism including a plurality of coöperating members, means for moving one of said members with respect to another, means for moving two of said members simultaneously, a single lever for actuating both of said last mentioned means and connections between 10 said lever and said two last mentioned means.

33. In a musical instrument, a plurality of note-sounding members, force applying elements coöperating with said parts, the 15 intensity of force which said elements are capable of exerting being variable, a series of devices for varying the intensity of force exerted by some of said elements as compared to others, manually controlled means 20 for actuating said devices said means including two controlling elements movable with respect to each other and also movable together, means for moving said elements with respect to each other, and means, structurally different from the means last mentioned, for moving said elements together.

34. In a pneumatically operated musical instrument, a series of note-sounding parts, a series of pneumatics therefor, a high vacuum exhaust trunk and a low vacuum exhaust trunk, a series of valves controlling communication between said pneumatics and said trunks, and means for actuating said valves at will, said means comprising a handle, two valve-controlling elements movable with respect to each other, and means controlled by said handle for moving said elements.

35. In a musical instrument, a plurality of note-sounding parts, force applying elements coöperating with said parts, the intensity of force which said elements are capable of exerting being variable, a series of devices for varying the intensity of force exerted by some of said elements as compared to others, manually controlled means for actuating said devices, said means comprising a manipulatable part, mechanism controlled by said part adapted to actuate materially variable numbers of devices in 50 said series, and correspondingly variably acting mechanism for indicating the particular force applying elements affected.

36. In pneumatically operated musical instruments, a series of note-sounding parts; a 55 series of pneumatics therefor, a series of valves for said pneumatics, a series of valve chambers, a plurality of conduits adapted to be placed in communication with said chambers, a series of elements each of which is 60 provided with means for controlling communication between said chambers and conduits, and a rotatable structure, said structure adapted, when rotated in a given direction, to successively actuate determined 65 elements in said series of elements while substantially simultaneously releasing other elements, previously subjected to actuation thereby, from its influence.

In witness whereof, I subscribe my signature, in the presence of two witnesses.

CHAS. P. HIDDEN.
